DRAW PRESS

Roy F. Dehn, Wickliffe, and William E. Ward, Shaker Heights, Ohio, assignors to The Cleveland Crane & Engineering Company, Wickliffe, Ohio, a corporation of Ohio

Application June 11, 1952, Serial No. 292,828

6 Claims. (Cl. 113—38)

The present invention relates to crank operated presses and the like, particularly adapted for deep drawing operations.

The principal object of the present invention is the provision of a new and improved crank operated draw press or the like, having a crank driven at a substantially constant rate and a ram reciprocated thereby through mechanism operative to produce a substantially constant, relatively slow rate of movement of the ram throughout the drawing portion of its stroke, and a relatively rapid return movement following the drawing stroke.

A more specific object of the invention is the provision of a new and improved crank operated draw press having a ram connected with the crank pin or eccentric thereof through two pivotally connected levers constituting a toggle linkage, one of which levers is pivotally connected with the crank pin and the other pivotally connected with the ram, and means operated in synchronism with movement of the crank to shift the pivotal connection between the two levers to one side of a line through the axis of the crank shaft and the center of the pivotal connection between the ram and the lever connected therewith, the movement of the pivotal connection being synchronized with the crank during the drawing stroke movement thereof to cause the resultant movement of the ram to be at a substantially constant rate and less than the maximum speed of the crank pin so that the draw stroke of the ram occurs during movement of the crank substantially in excess of 180°, the pivotal joint being returned to the aforementioned line at substantially the end of the drawing portion of the revolution of the crank pin whereby the maximum pressure exerted by the crank on the ram is through a straight line linkage.

Another object of the invention is the provision of a new and improved press of the character referred to in which the pivotal joint of the two levers forming a toggle linkage interconnecting the crank pin and ram is moved in an elliptical path during each revolution of the crank, the elliptical path extending across the line through the axis of the crank shaft and the center of the pivot between the ram and the lever connected thereto, the pivotal connection having its greatest excursion from the aforementioned line during the return stroke movement of the crank pin whereby the crank pin and levers return the ram to its uppermost position during movement of the crank shaft through an angle appreciably less than 180°.

The invention resides in certain constructions and combinations and arrangements of parts and further objects and advantages will be apparent to those skilled in the art to which it relates from the following description of the preferred embodiment described with reference to the accompanying drawings forming a part of this specification in which,

Fig. 1 is a front view partly in elevation and partly in section of a draw press embodying the invention;

Fig. 2 is a sectional view taken substantially along line 2—2 of Fig. 1;

2

Fig. 3 is a schematic representation of the relative movements between certain parts of the press mechanism throughout a cycle of operation;

Fig. 4 is a graph representing the speeds of the die slides or rams of a conventional crank operated draw press and the press shown in Figs. 1 and 2; and

Fig. 5 is a graph illustrating the relative pressure-inches stroke of a conventional crank operated press and the press shown in Figs. 1 and 2.

Referring to the drawings, the crank operated draw press shown comprises a conventional frame 10 having a die bed 11 and spaced upright guides 12 in which a die slide or ram 13, which may be of any suitable construction, slides vertically. The ram is adapted to carry a suitable punching die which cooperates with a die attached to the bed to form a relatively deep draw in a metal blank. The dies are not shown as they are well known to the trade, nor is the usual blankholding means comprising die cushions, pressure pads, etc. The particular press shown has a drawing stroke of approximately fifteen and one half inches and the dies will draw metal during approximately seven and one half inches of the stroke, it being understood that a separation between the dies of at least the depth of the draw is required to permit removal of the drawn work.

A crank shaft 16 is suitably journaled in the upper part of the frame and is driven by a pair of bull gears 17, 18 attached to the ends thereof. The bull gears are driven by pinions 19, only one of which appears in the drawings, which are supported on a drive shaft 20 at the rear of the press. The shaft 20 is preferably driven by an electric motor 21 through a conventional one revolution clutch mechanism 22 which may be of any well known construction and includes a suitable control device such as a push button, pedal or lever, not shown, which is actuated by the press operator to cause the clutch to drive the shaft 20 and rotate the bull gears 17, 18 through one revolution in a counterclockwise direction as viewed in Figs. 2, 3. The details of the driving mechanism for the shaft 16 are not shown since such drives are well known in the art. The crank shaft 16 has a crank pin or eccentric 24, and in the particular press shown, the eccentric has a throw of five inches; that is to say, the center of the eccentric is offset from the axis of the crank shaft five inches.

The eccentric 24 is connected with the ram 13 through a bell crank lever or eccentric strap 25 journaled thereon and a link or lever 26 pivotally connected at one end to the arm 27 of the bell crank lever 25 and at the other end to the ram 13, the arm 27 and link 26 forming a toggle-like linkage. The arm 27 of the bell crank lever comprises two spaced flanges 28, 28' between which the upper end of the link 26 is received. This end of the link has a tubular bearing therein for receiving a wrist pin 31 supported in openings through the flanges 28, 28'. The lower end of the link 26 is pivotally connected to the ram 13 by a knuckle joint 32. This linkage between the eccentric 24 and ram is similar to a toggle and by oscillating the bell crank lever 25 about the eccentric, the center of the joint comprising the wrist pin 31, which may be termed the knee of the linkage, can be shifted from one side to the other of a line *a*, which extends through the axis of the crank shaft and the center of the joint 32, to thereby raise the ram 13 or produce relative movement between the ram and the eccentric or crank pin 24. The line *a* is referred to as the vertical center line of the press and, as viewed in Figs. 2, 3, the left hand side thereof is referred to as the forward or front side and the right hand side is referred to as the rear side.

By shifting the joint comprising the pin 31 forwardly of the line *a* and returning it to the line during the down-

ward sweep of the eccentric 24, the resultant rate of movement of the ram downwardly can be constant and substantially below the speed at which it would move if connected to the eccentric by a solid pitman, as in conventional crank press constructions. By shifting the joint comprising the pin 31 to the rear of the line *a* during the up-sweep of the eccentric, the resultant upward movement of the ram 13 is substantially in excess of the speed at which it would move if connected to the eccentric by a solid pitman, and the return stroke of the ram 13 can be effected by considerably less than 180° rotation of the eccentric.

According to the invention the bell crank lever 25 is oscillated in timed relation to the rotation of the eccentric so that the joint formed by the pin 31 moves in an elliptical path *d*, as seen in Fig. 3, which intersects the vertical center line *a*, and its excursion to the forward side of the line is appreciably less than that rearwardly of the line. The center of the joint formed by the pin 31 coincides with line *a* at the time the eccentric 24 reaches the end of its down-sweep at which time its center is likewise coincident with the line *a* so that the force transmitted to the ram 13, which at this point is at maximum, is through a straight line linkage. Any suitable mechanism may be employed to impart the desired movement of the crank lever 25 and lever 26.

In the preferred form of the invention, the second or other arm 35 of the bell crank lever 25 is pivotally connected to one end of a guide link 36 the other end of which is pivotally anchored to a bracket 37 bolted to the press frame. The link 36 has cylindrical bearings in the ends thereof and the bearing in one end is pivoted to the bracket 37 by a wrist pin 38 which extends therethrough and is supported in openings through two spaced parallel lugs 39 of the bracket, and the other end of the link 36 has its bearing pivoted to the arm 35 of the bell crank lever 25 by a wrist pin 42 extending therethrough and supported in openings in two spaced lugs 43, 44 which comprise the arm 37 of the bell crank lever 25. The center of the pivot pin 42 lies on a line extending at about 135° from a line through the centers of the eccentric 24 and the joint comprising the pin 31; and when the shaft 16 rotates the eccentric, the link 36 causes the center of the pivot pin 42 to travel in an arc extending at approximately 45° from the horizontal line through the axis of the shaft 16. The line described which extends through pin 42 is, in effect, arm 35 and it will be seen that it extends into the quadrant bounded by the vertical center line *a* and the horizontal line through the axis and into which the eccentric moves when it crosses the vertical center line in the initial movement thereof to effect a drawstroke. By anchoring the arm 35 of the bell crank lever 25 as described, the bell crank lever 25 is oscillated about the eccentric 24 as the latter is rotated to effect the shifting of the joint at the pin 31 and actuate the ram as described.

As mentioned previously, the press shown by way of example has a ram stroke of fifteen and one-half inches, and to obtain the most desirable operating characteristics of the press the effective length of the arm 27 measured from the center of the eccentric 24 to the axis of the pin 31 is seventeen inches; the length of lever 26 measured from the center of pin 31 to the center of the joint 32 is twenty-three inches; the length of the arm 35 measured from the center of the eccentric 24 to the center of pin 42 is fifteen inches, and the length of the guide link 36 measured from the center of pin 38 to the center of pin 42 is sixteen inches. The axis of pin 38 is located from the vertical center line *a* twenty-three and one-half inches and is two and three quarter inches below the horizontal line through the axis of the crank shaft. It is to be understood that these dimensions are merely examples and they may be varied for presses having different ram strokes, although the

pin locations and lengths of the arms, lever and link should remain in proportion to the stroke approximately as indicated.

It is to be understood that only those parts of the press have been shown and described which are essential to the understanding of the mechanism for operating the ram, and that additional well known structures, such as an adjusting mechanism between the ram and the link 26, have not been shown as they are well known in the trade.

The operation of the ram can be readily understood by referring to Fig. 3 which shows various elements of the press schematically and in their respective positions at different angular positions of the crank shaft. When the press is idle, the crank shaft 16 is in a position in which the center of the eccentric 24 is at 24a and since link 36 limits or guides the portion of the arm 35 in which the wrist pin 42 is supported in the arcuate path *b* the pin 42 is at 42a and the bell crank lever 25 is thus positioned about the eccentric so that the joint comprising wrist pin 31 is at 31a, which is considerably to the rear of the vertical center line, and the end of link 26 comprising the joint 32 between the link and ram 13 is at 32a, the upper end of its travel or stroke. As counterclockwise rotation of the crank shaft is initiated, the eccentric is moved in the circular path *c* upward and across center line *a*, moving the joint comprising wrist pin 42 upwardly along arc *b* which tilts the bell crank lever 25 clockwise about the eccentric and moves the joint comprising pin 31 along the elliptical path *d* toward the center line *a* thereby tending to straighten the angle between arm 27 of the bell crank lever 25 and the lever 26 which lowers the ram through a greater distance than the vertical movement of the eccentric.

As the eccentric sweeps through the first quadrant at the left of vertical line *a*, the crank lever 25 continues clockwise about the eccentric and when the center of the eccentric reaches the point 24b the respective joints comprising pins 42 and 31 are at 42b and 31b, and the angle between arm 27 and lever 26 is rapidly approaching 180°. The center of the joint 32 is then at 32b, and the ram is approaching the lower half or draw portion of its stroke. As the eccentric moves to point 24c the joint at pin 42 is moved to 42c and the bell crank lever is swung to move the joint comprising pin 31 to 31c at the left or front of the line *a* and thereby break the straight angle between the arm 27 and lever 26, which action tends to raise the ram. The eccentric at this point, however, is sweeping downwardly at a rate in excess of the rate at which the breaking of the arm 27 and lever 26 tend to raise the ram 13 so that the resultant rate of descent of the ram is the algebraic sum of these two factors and the joint 32 is at 32c, which is in the draw portion of its stroke. When the center of the eccentric reaches 24d it is traveling at its greatest rate in the vertical component and at the same time the joint comprising pin 31 is approaching its maximum excursion to the front of line *a* and increasing the break from the straight angle between arm 27 and lever 26 so that the rate at which it tends to raise the ram is increased to closely correspond to the increase in the downward rate of the eccentric.

As the center of the eccentric reapproaches line *a*, bell crank lever 25 is moved counterclockwise thereabout to swing the joint comprising pin 31 back toward line *a* thereby adding to the downward movement of the ram and compensating for the reduction of speed imparted to the ram by the eccentric. When the center of the eccentric is at its lowermost position indicated at 24d and on line *a* the pin 42 is at 42d and the crank lever 25 is swung so that the joint comprising pin 31 is at 31d and on the line *a*. In this event the entire tonnage imparted from the eccentric to the ram is through the resultant straight line linkage.

As the crank shaft continues its rotation and moves the eccentric in its upward sweep, the link 36 forms a pivot about which lever 25 rotates whereby the joint comprising pin 31 is swung wide and rapidly to the rear of the line *a* and imparts a quick withdrawing movement to the ram 13. This withdrawing action of the levers 25 and 26 combining with that of the eccentric quickly returns the ram to its uppermost position, at which point the crank shaft is stopped.

In connection with the transmission of force from the eccentric to the ram, the excursion of the pivot joint at pin 31 forwardly of the vertical center line *a* during the draw stroke is limited so that the lever 26 is not shifted over about 11° from vertical whereby the lateral thrust on the ram guides is low and will not be sufficient to cause appreciable wear or inaccuracy in the operation of the dies. It will be noted that the maximum pressure is applied at or near the in-line position of the arm 27 and link 26.

It is apparent that the downward or drawing stroke of the ram is effected by an appreciably greater angular movement of the crankshaft 16 than that required to return the ram to its uppermost position. In the press shown, the drawing or working stroke occurs during about 220° movement of the crankshaft as against 180° movement of the crankshaft of a conventional crank operated press. Thus, the R. P. M. of the crankshaft of the improved press can be substantially increased over that of a conventional crank operated press without increasing the maximum drawing speed of the ram.

The relative rates of travel of the ram of the improved press and that of a conventional crank operated press having the same length of stroke is illustrated in the graph shown in Fig. 4. In this graph line 50 represents the lineal movement of the ram 13 relative to the angular movement of the crankshaft 16 which is represented by the parallel longitudinally extending lines which are spaced from one another to represent ten degrees of crankshaft rotation. The zero degree or starting position of the crankshaft is represented by the first line at the left end of the graph. It will be seen that during the first one hundred degrees of rotation of the crankshaft the ram is lowered through approximately the first half of the draw stroke, which merely brings the dies together. The last half of the stroke in which the work is drawn by the dies, the rate of travel of the ram or the movement thereof per degree of rotation of the crankshaft is substantially constant, until just before the end of the stroke. The last half of the stroke that is, the working or drawing portion of the stroke is effected by about one hundred and twenty degrees of rotation of the crankshaft. The return stroke of the ram occurs in about one hundred and forty degrees of movement of the crankshaft. Broken line 51 of the graph illustrates the movement of the ram of the conventional crank press and it will be seen that the movement of the ram per degree of rotation of the crankshaft during the greater part of the drawing portion of the stroke is considerably in excess of that of the improved press. As a result, the R. P. M. of the crankshaft of the conventional press must be considerably less so that the maximum permissible draw speed is not excessive. In fact, the R. P. M. of the improved press can be 82% higher than that of conventional crank presses having like ram strokes.

The improved press not only is capable of operating at a much higher speed than conventional crank operated presses of comparable strokes, but it is capable of delivering considerably greater tonnage to the ram from equal power input. Referring to Fig. 5, the graph therein illustrates tonnages by the vertical appearing lines and the depth of the drawing die is indicated by the horizontal appearing lines spaced apart to represent half inches of depth of the die, the bottom of the die being represented by the bottom line. The broken curved line 54 represents the pressure curve on the ram of a

conventional crank operated press and the curved line 55 represents the pressure curve on the ram of the improved press having the same power and ram stroke as the conventional press. It will be seen that the improved press delivers considerably greater tonnage to the ram in the upper part of the drawing stroke and that the tonnage delivered to the ram of the conventional press does not approach that of the improved press until the last inch or so of the stroke.

It is apparent that the objects enumerated as well as others have been attained and that a new and improved press of the character referred to has been provided which materially increases the speed of operation of metal drawing operations over conventional crank operated presses without exceeding safe drawing speeds, and that the efficiency of the press with respect to the tonnages deliverable to the punch ram is substantially increased over that of conventional crank operated presses. While but one form of the invention has been shown and described, it is our intention to cover hereby all other forms, modifications and adaptations, thereof falling within the claims appended hereto.

Having thus described our invention, we claim:

1. In a draw press, a frame, an eccentric journaled in said frame, means to rotate said eccentric in one direction about a fixed axis, a ram, means to move said ram in a drawing stroke comprising two levers connected together by a pivot joint, one of said levers being journaled on said eccentric and the other lever pivotally connected with said ram, and means operated in synchronism with the rotation of said eccentric to move said joint to one side of a line through said axis and the center of the pivot connection between said ram and said lever connected thereto during the ram drawing stroke movement of said ram and to return said joint substantially to said line as said eccentric reaches the extremity of its drawing stroke movement whereby the centers of said joint and said eccentric lie substantially on said line, and operable to move said joint to the opposite side of said line during the ram return movement of said eccentric, the excursion of said joint on said opposite side of said line being substantially in excess of its excursion to the first mentioned side of said line.

2. In a draw press, a frame, a ram slideable in said frame in a drawing stroke, an eccentric journaled in said frame, means to rotate said eccentric in one direction about a fixed axis, a drive between said eccentric and ram comprising two levers connected to one another by a pivot joint, one of said levers being pivotally connected with said eccentric and the other of said levers pivotally connected with said ram, an arm rigidly connected with the first mentioned lever and projecting into a quadrant defined by a line in a plane containing said levers extending through said axis and the center of the pivotal connection of said ram and said lever connected therewith and a second line through said axis and normal to the first mentioned line and said axis and which quadrant is initially entered by said eccentric passing through the first mentioned line in moving said ram in its drawing stroke, and a pivoted lever for guiding a point on said arm in an arcuate path extending at approximately 45° with respect to said second line and having its pivot point to one side of said second line and in the quadrant adjoining the first mentioned quadrant and on the other side of the second line whereby said one lever is oscillated by rotation of said eccentric about said axis to swing said joint in an elliptical path intersecting the first mentioned line.

3. In a draw press, a frame, a ram slideable in said frame in a drawing stroke, an eccentric journaled in said frame, means to rotate said eccentric in one direction about a fixed axis, a drive between said eccentric and ram comprising two levers connected to one another by a pivot joint, one of said levers being pivotally connected with said eccentric and the other of said levers pivotally con-

connected with said ram, an arm rigidly connected with the first-mentioned lever and projecting into a quadrant defined by a line in a plane containing said levers extending through said axis and the center of the pivotal connection of said ram and said lever connected therewith and a second line through said axis and normal to the first mentioned line and which quadrant is initially entered by said eccentric passing through the first-mentioned line in moving said ram in its drawing stroke, and means for guiding a point on said arm comprising a link pivoted to said frame at a point in a plane parallel to said second line between said axis and ram and in a quadrant adjoining the first-mentioned quadrant, said link projecting into said quadrant and being pivotally connected to said arm.

4. In a draw press, a frame, a ram vertically slidable in said frame, a first lever pivotally connected at one end to said ram for reciprocating the latter, the pivotal connection between said lever and said ram moving along a vertical line, an eccentric rotatably supported in said frame with its axis of rotation normal to and intersecting said line, an eccentric strap rotatably supported by said eccentric and including an arm pivotally connected to the other end of said lever and forming a toggle linkage therewith, lever means connected to said strap for positioning said arm along said line when the center of said eccentric is at its lowest point in its path of rotation and for causing the pivotal connection to swing to one side of said line for more than 180° but less than 270° of rotation of the eccentric from its lower position and then to swing to the other side of said line until the center of said eccentric again reaches its lowest point with the movement of the pivotal connection between said arm and said lever defining a substantially elliptical path generally transverse to and intersecting said line with the excursion of the connection to the first-mentioned side of the line being substantially greater than its excursion to the second-mentioned side of said line.

5. In a draw press, a frame, a ram vertically slidable in said frame, a first lever pivotally connected at one end to said ram for vertically reciprocating the latter, the pivotal connection between said lever and said ram moving along a vertical line, an eccentric rotatably supported in said frame with its axis of rotation normal to and intersecting said line, an eccentric strap rotatably supported by said eccentric and including a first arm pivotally connected to the other end of said lever forming a toggle linkage therewith and a second arm defining an obtuse angle with said first arm and extending into the quadrant in which the center of said eccentric begins its downward movement upon rotation thereof, lever means connected to said second arm for positioning said first arm along said line when the center of said eccentric is at its lowest point in its path of rotation and for constraining the pivotal connection between said first arm and said lever to swing to one side of said line for more than 180°

but less than 270° of rotation of the center of the eccentric from its lowest position and then to swing to the other side of said line until the center of said eccentric again reaches its lowest point with the movement of the pivotal connection between said arm and said lever defining a substantially elliptical path generally transverse to and intersecting said line and with the excursion of said pivotal connection to the first-mentioned side of the line being substantially greater than its excursion to the second-mentioned side of said line.

6. In a draw press, a frame, a ram vertically slidable in said frame, a first lever pivotally connected at one end to said ram for reciprocating the latter, the pivotal connection between said lever and said ram moving along a vertical line, an eccentric rotatably supported in said frame with its axis of rotation normal to and intersecting said line, an eccentric strap rotatably supported by said eccentric and including a first arm pivotably connected to the other end of said lever forming a toggle linkage therewith and a second arm defining an obtuse angle with said first arm and extending into the quadrant in which the center of said eccentric begins its downward movement upon rotation thereof, a pivoted lever pivotally connected to said second arm for constraining a point thereon to move along an arc in said quadrant and for positioning said first arm along said line when the center of said eccentric is at its lowest point in its path of rotation and to cause the pivotal connection to swing to one side of said line for more than 180° but less than 270° of rotation of the eccentric from its lower position and then to swing to the other side of said line until the center of said eccentric again reaches its lowest point with the movement of the pivotal connection between said arm and said lever defining a substantially elliptical path generally transverse to and intersecting said line with the excursion of the connection to the first-mentioned side of the line being substantially greater than its excursion to the second-mentioned side of said line, and means pivotally supporting the last-said lever in the quadrant entered by the center of the eccentric upon leaving the first-said quadrant.
